UNITED STATES PATENT OFFICE.

JOSEPH DYER AND GEORGE H. LEONARD, OF FAIRFIELD, MAINE, ASSIGNEES TO
MAINE SCREEN AND VENTILATOR COMPANY, OF FAIRFIELD, MAINE, A CORPO-
RATION OF MAINE.

SCREEN.

1,065,304.

Specification of Letters Patent. Patented June 17, 1913.

Application filed September 10, 1912. Serial No. 719,670.

To all whom it may concern:

Be it known that we, JOSEPH DYER and GEORGE H. LEONARD, citizens of the United States, residing at Fairfield, in the county of 5 Somerset and State of Maine, have invented new and useful Improvements in Screens, of which the following is a specification.

The invention relates to window screens and has for an object to provide a removable 10 screen for use on window casings and the like.

The invention embodies, among other features, a frame having the usual screen wire secured thereto and arranged to slide on 15 the usual strips of a window casing, spring-like means being employed for retaining the frame on the casing to prevent rattling thereof, with means for locking the frame on the casing without disturbing the sliding 20 movement of the frame, the said frame being readily removable from engagement with the casing and as easily engaged therewith.

In the further disclosure of the invention 25 reference is to be had to the accompanying drawings, constituting a part of this specification, in which similar characters of reference denote corresponding parts in all the views, and in which—

30 Figure 1 is a front elevation of a window casing showing our device applied thereto; Fig. 2 is a rear elevation of a window casing showing our device applied thereto; Fig. 3 is a horizontal sectional view taken on the 35 line 3—3 in Fig. 1; and Fig. 4 is a fragmentary perspective view of the frame.

Referring more particularly to the views, we disclose a window casing 10 having the usual vertical strips 11 thereon for retaining 40 the ordinary window sashes in sliding engagement with the window casing.

A rectangular screen frame 12 is provided with the usual screen wire 13 mounted on the frame and the said frame has a guide 45 plate 14 projecting beyond one side of the same to extend across the front face of one of the strips 11, the mentioned guide plate being arranged to lie in a plane with the face of the frame 12 so that when the frame 50 is mounted on the window casing 10 the same will be interposed between the strips 11 as shown. In order to prevent any rattling of the frame 12 when the same is mounted on the window casing and to aid in 55 sliding the frame vertically on the strips 11

of the window casing, a leaf spring 15 has an end thereof rigidly secured to the frame 12 by a pin 16, the free end of the said spring being provided with a longitudinally extending slot 17 through which extends a 60 pin 18 secured to the frame 12, with the free or slotted end of the spring 15 slidable on the frame 12, the medial portion of the spring being normally spaced from the frame and engaging a side of the strip 11 65 having the guide plate 14 projecting thereover. A guide lug 19 projects laterally from the spring 15 across the inner side of the strip 11, engaged by the spring 15, thus retaining one side of the frame in slidable 70 engagement with the mentioned strip so that the frame can be slid vertically on the window casing.

In order to retain the other side of the frame in slidable engagement with the 75 window casing, a slotted locking member 20, provided with a handle 21, is mounted to slide on the inner side of the frame 12 with an end 22 of the locking member projecting across the other strip 11 of the window casing, pins 23 being passed through the slots of the locking member 20 in order to retain the same in engagement with the frame 12 and also permit a sliding movement of the locking member, a leaf spring 24, provided 80 with slots 25 in the ends thereof, being mounted on the frame 12 with pins 26 passing through the slots 25 and the medial portion of the spring 24 engaging the locking member 20 to normally retain the same in 85 locked position. It will now be seen that when the frame 12 is mounted on the window casing 10, the guide lug 19 together with the guide plate 14, will retain one side of the frame in slidable engagement with one of the strips of the window casing and the end 22 of the locking member 20 will retain the other side of the frame 12 in slid 90 able engagement with the other strip of the window casing, the locking member 20 being 95 also adapted to prevent the accidental removal of the frame 12 from slidable engagement with the strips 11 of the window casing 10, while at the same time the frame can be readily moved vertically on the window casing, and the leaf spring 15, engaging a face of one of the strips 11, will hold a face of the frame 12 against the face of the other strip, thus preventing any rattling of the frame on 100 the window casing. In order to further se- 105 110

cure the frame 12 on the window casing in the manner mentioned, an auxiliary leaf spring 27 is rigidly secured to the frame 12 by the same pin 16 that connects the leaf 5 spring 15 to the frame, the mentioned leaf spring 27 being adapted to project upwardly and provided at the upper end thereof with a laterally extending portion 28 projecting over the upper face or edge of the frame 12 when the frame is in position on the window 10 casing, the leaf spring 27 at the point of formation of the laterally extending portion 28 being adapted to be normally spaced from the frame 12 and abut against one of the strips 11, thus exerting sufficient pressure on the upper end of the frame so that the side 15 of the frame upon which the locking member 20 is mounted will be held against a face of one of the strips to prevent any undue 20 displacement of the frame 10 on the window casing. The usual handle 29 is mounted on the frame 12 in order to facilitate the operation of sliding the frame on the window casing and from the foregoing description it 25 will be seen that by simply sliding the locking member 20 against the action of the spring 24, the portion of the frame having the locking member thereon can be moved outwardly from engagement with one of the strips 11 and the opposite side or portion of 30 the frame can then be moved away from the window casing, thus removing the leaf spring 15 and guide lug 19 from engagement with the other strip 11 and resulting 35 in the entire removal of the screen from the window casing, while at the same time, when the frame is moved on the window casing, the springs 15, 27, together with the guide lug 19 and locking member 20, will retain 40 the frame 12 in slidable engagement with the window casing so that the frame can be readily moved upwardly or downwardly on the strip 11 thereof, the guide plate 14 being provided to prevent the removal 45 of the side of the frame 12 opposite to the side of the frame having the locking member 20 thereon.

Having thus described our invention, we claim:

50 1. In a screen, the combination with a frame, of a leaf spring having one end thereof secured to the frame and the other end thereof slidable on the frame with the medial portion of the spring adapted to engage one 55 of the strips of a window casing, a guide lug projecting from the spring to engage the said strip, an auxiliary spring secured to the frame and provided with a laterally extending portion projecting around the upper end 60 of the frame with the medial portion of the auxiliary spring abutting against the said strip, a guide plate secured to the frame and projecting from one side thereof to extend across a portion of the window casing, and 65 a locking member slidable on the said frame

to engage an opposite strip of the said window casing.

2. In a screen, the combination with a frame, of a leaf spring having one end thereof secured to the frame and the other end thereof slidable on the frame with the medial portion of the spring adapted to engage one of the strips of a window casing, a guide lug projecting from the spring to engage the said strip, an auxiliary leaf spring secured to the frame and provided with a laterally extending portion projecting around the upper end of the frame with the medial portion of the auxiliary spring abutting against the said strip, a guide plate secured to the frame and projecting from one side thereof to extend across a portion of the window casing, a slotted locking member, pins extending through the slot of the locking member to slidably connect the same with the said frame with an end of the locking member projecting over an opposite strip of the said window casing, a handle for the locking member, and a spring on the said frame and engaging the said locking member to normally retain the same in locked position and in engagement with the said opposite strip.

3. A screen comprising a frame having screen wire thereon, a leaf spring having one end thereof rigid on the frame and the other end thereof slidable on the frame with the medial portion of the leaf spring normally spaced from the frame, a guide lug projecting from the said spring, a guide plate projecting beyond one side of the said frame, and a spring-engaged locking member mounted on the other side of the said frame for locking the said frame on a window casing.

4. A screen comprising a frame having screen wire thereon, a leaf spring having one end thereof rigid on the frame and the other end thereof slidable on the frame with the medial portion of the leaf spring normally spaced from the frame, a guide lug projecting from the said spring, a guide plate projecting beyond one side of the said frame, a spring-engaged locking member on the other side of the said frame for locking the said frame on a window casing, and an auxiliary spring having one end thereof rigidly secured to the frame and the medial portion thereof normally spaced from the frame to engage the window casing.

5. In a screen, the combination with a rectangular frame for slidable engagement with a window casing, of a guide plate projecting from one side of the frame, a leaf spring mounted on the frame and having a medial portion thereof normally spaced therefrom, the said leaf spring being arranged adjacent the said guide plate, a lug on the said leaf spring and spaced from the guide plate, and a spring-engaged locking member mounted

on the other side of the said frame and adapted to engage the window casing.

6. In a screen, the combination with a rectangular frame for slidable engagement 5 with a window casing, of a guide plate projecting from one side of the frame, a leaf spring mounted on the frame and having a medial portion thereof normally spaced therefrom, the said leaf spring being arranged adjacent the said guide plate, a lug 10 on the said leaf spring and spaced from the guide plate, a spring-engaged locking member mounted on the other side of the said

frame and adapted to engage the window casing, and an auxiliary leaf spring secured 15 to the frame and having a medial portion thereof adapted for engagement with the window casing when the said frame is mounted to slide thereon.

In testimony whereof we affix our signatures in presence of two witnesses.
